ELECTROMANUAL RAILROAD SWITCH LOCK
AND SIGNAL CIRCUIT CONTROL WITH
EMERGENCY RELEASEOscar S. Field and Ralph W. Hewes, Rochester,
N. Y., assignors to General Railway Signal Com-
pany, Rochester, N. Y.

Application September 4, 1944, Serial No. 552,637

10 Claims. (Cl. 246—146)

1

This invention relates in general to a lock device, and has more particular reference to an electric lock for use in connection with hand-operated railway track switches.

Many railroads have hand-operated track switches which connect the main track with turnout tracks, commercial sidings, passing tracks and the like, which hand-operated track switches are normally locked with their release under the joint control of a central operator and the switchman at the track switch. Such an organization together with suitable automatic controls not only provides safer operation of main line traffic, but keeps the traffic under the direct control of the central operator. In such cases, it is usual to provide what is commonly known as an electric switch lock which can be governed both by automatic traffic controlled means and by suitable cooperation between the trainman at the switch and the central operator over suitable communication system. It will of course be appreciated that such electric locks are located on the ties supporting the track rails and thus are subject to extreme vibration and shocks.

With the above noted consideration in mind, one object of the present invention is to provide an efficient, rugged and practical switch lock adapted to accomplish the various functions and purposes required of electric switch locks in a modern centralized traffic control system.

Another object of the present invention is to provide an electric switch lock which is so constructed as to be immune to shocks and vibrations insofar as its false or unintended release of the lock is concerned.

Other objects, purposes and characteristic features of the present invention will be in part obvious from the accompanying drawings, and in part pointed out as the description of the invention progresses.

In describing the invention in detail, reference will be made to the accompanying drawings, in which like reference characters will be used to designate the corresponding parts throughout the several views, and in which—

Fig. 1 shows a typical switch layout having a hand-operated switch stand with an electric switch lock constructed in accordance with the present invention applied thereto;

Fig. 2 is a side view of the electric switch lock with certain parts shown in section as indicated by the section line 2—2 of Fig. 1;

Fig. 3 is a top view of the electric switch lock with the cover removed so as to show certain parts of the mechanism and contact structure;

2

Fig. 4 is a sectional end elevation of the electric switch lock taken on line 4—4 of Fig. 5;

Fig. 5 is a sectional side elevation of the electric switch lock taken on line 5—5 of Fig. 3; and

Fig. 6 is an organizational view of the proposed electric switch lock with the related parts shown in distorted positions in order to more clearly illustrate their operative functions, rather than to disclose the specific structure.

Referring more particularly to Fig. 1 of the drawings, an electric switch lock EL, constructed in accordance with the present invention, is indicated as associated with a hand-throw switch mechanism HT which is connected to the movable points of a track switch W. The movable points of the track switch W are interconnected by a front rod 6 which has a throw bar 7 connecting it to a crank arm 8 of the hand-throw mechanism HT. The crank arm 8 is operated through a limited arc by the hand-throw bar 9 when it is unlocked so that it can be moved from a normal position to a reverse position or from a reverse position to a normal position. Such a hand-throw mechanism HT may be of any suitable type and will thus not be described in further detail. Fig. 6 shows a diagrammatic illustration of the functional operation of such a hand-throw mechanism HT.

As viewed in Figs. 1 and 4, it will be seen that the hand-throw bar 9 is held in a normal position by the electric switch lock by reason of a locking latch 10 which has an extending foot pedal portion 11. This latch 10 is pivoted on a shaft 12 (see Fig. 3).

Referring to Figs. 2, 4 and 6, it can be seen that the latch 10 is normally in a position to hold the hand-throw bar 9 in its normal position, and the latch 10 is held in such position by a detent 13, which detent is pivoted at 14 and has a hole at its other end which registers with a hole in a lug 15 so that the shackle of padlock P can be inserted. This locks the latch 10 and its releasing control to prevent unauthorized tampering.

The hand-throw bar 9 is pivoted at 16 and around the shank of the hand-throw bar is a clamp 17 having two extending pivot portions 18 and 19 (see Fig. 2). A hold-open bar 20 is attached to the pivot 18, but if the electric lock were to be employed to lock the hand-throw bar 9 in its reverse position, it should be understood that the opposite pivot point 19 would be employed. Also, the hold-open bar 20 rests on an inclined portion 21 of the latch base member 27, but if the lock mechanism were to be employed

to lock the hand-throw bar 9 in its reverse position, as above mentioned, then the hold-open bar 20 would enter its receiving space from the right (as viewed in Fig. 2) and rest on the opposite inclined surface 22 of the latch base member.

The electric lock EL comprises an outer casing 25 having a hinged cover 26 with a suitable hasp and padlock 55 (see Figs. 2 and 5). Within the outer casing 25 is located the electromagnetic locking organization. As viewed in Fig. 4, the pedal-latch base 27 is attached to the side of the lock casing 25, and is held in position by suitable bolts as seen in Fig. 3. The pedal-latch base 27 has a recessed portion adjacent the lock casing 25 for receiving the hand-throw bar 9, while the inner portion of the pedal-latch base 27 provides an enclosed housing for the tappet bar 46 and lock rod 50 connecting with the inner portion of the lock casing 25. The lock casing 25 is also supplied with a suitable opening near its base for allowing the connection of conduit for bringing in lead wires to the contacts and electromagnet of the lock mechanism.

Referring to Fig. 5, it will be seen that an inner case structure 28 of suitable insulating material provides a mounting for the terminal posts 29, electromagnet core 30, and various of the operating means as will presently be described. The lower portion of this inner structure 28 has a base 31 connected to the outer casing 25, while the upper portion of this inner structure 28 is enclosed by a cover plate 32 which is spring mounted to the cover 26 so as to properly assume a position to tightly enclose the inner structure 28 when the cover 26 is moved to its closed position. In this way, the inner structure 28 insulates the contacts and cam operating organization from the outer casing to provide protection against frost and moisture condensation upon changes in temperature and relative humidity. Also, mounted to the top plate 32 is an indicator lamp 33 which is provided in such a position that light from it can pass through a glass closed opening 34 included in the cover member 26.

As seen in Fig. 3, a shaft 35 is supported by the side plates 36 of the inner structure 28, and this shaft 35 is provided with a raised cam portion and a slotted portion for receiving the fingers of the release arm 41, as will presently be described. The cam shaft 35 is normally held in the position shown in Fig. 3 against the bias of a coil spring 37, and when in this position the contact operating cam 38 is in a recess on the cam shaft 35 so as to cause the contacts mounted on arm 39 to assume their biased positions. Referring to Fig. 5, it will be seen that the contact arm 39 is pivoted at 40 and is biased by a spring 41 to close its back contacts. The cam member 38 is pivoted to the wall of the inner structure 28 at 42 and has a roller at its opposite end which rides on the shaft 35, while extending from the member 38 is an arm 43 which engages a projection on the arm 39 so that if the cam shaft 35 is moved to the left by spring 37 (as seen in Fig. 3), the roller on the arm 38 rides up the cam surface of the shaft 35 and causes the contact arm 39 to be moved for compressing the spring 41 and closing the front contact points 82 connected to the arm 39. These contacts connected to arm 39 may be conveniently termed "latch contacts" since they are operated as soon as latch 10 is released from detent 13.

Referring to Fig. 4, it will be seen that the pedal-latch 11-10 acts through an arm 45 to move

the tappet bar 46 to the left which engages a lever or release arm 47 through a lost motion slot connection to rotate the lever 47 a limited degree on its pivot point 48 so as to cause the cam shaft 35 to be moved to the right and normally compress spring 37. When the padlock detent 13 is removed so as to release the pedal-latch 11-10, then the pedal-latch assumes a position where the arm 49 comes in contact with the lock rod 50 due to the weight of the pedal portion 11 and the bias of spring 37. In other words, such release of the pedal-latch allows a certain free movement thereof so that the spring 37 can cause the cam shaft 35 to be moved to a left-hand position in which the contact arm 39 is caused to assume a front contact making position.

Since the lock rod 50 is biased to the left by a relatively strong spring 51, the lock rod 50 holds the pedal-latch against further movement, and does not allow the lock rod 50 to engage the balanced locking stop member 52. It can be seen in Fig. 4 that the lower portion of the casing 25 has two upwardly extending bosses between which the locking stop member 52 is located and upon which it is balanced on a pivot shaft 53, so that it may be rotated into a position to in part close the guiding holes for the lock rod 50 and thus prevent its manual movement against the bias spring 51. More specifically, it can be seen in Fig. 5 that the locking stop member 52 assumes a position to partially close the holes 54 and in such position the lock rod 50 if forced to the right (as seen in Fig. 4) by reason of pressure applied on the pedal portion 11, the stop member 52 would be pushed against the upstanding boss of the base 25. In other words, the locking of the lock rod 50 is effected by dissipating any applied force against the relatively strong upstanding boss of the casing 25.

When the cam shaft 35 is in a normal position as shown, an extending arm 60 pivoted on the side plate of the inner structure 28 at 61 has a roller at its left-hand end engaging the cam shaft 35 so as to be moved downwardly and force a plunger 62 downwardly against the spring 63, and thereby force or insure that the locking stop member 52 is in a position to prevent longitudinal movement of the lock rod 50 to a releasing position (i. e., where latch 10 allows movement of bar 9). It can be seen in Fig. 5 that the plunger 62 is provided with suitable guide members attached to the bottom plate 31 of the inner structure and serving as a support for the spring 63. At the upper end of the plunger 62 is an enlarged portion against which the pivoting cam arm 60 can rest as seen in Figs. 4 and 5. Also, the arm 60 has a set screw adjusted lower portion to vary the extent of its effect on plunger 62.

When the cam shaft 35 assumes its biased position, then the arm 60 is moved upwardly due to the bias of spring 63 on the plunger 62, and with the plunger 62 thus raised to a position disengaging the locking stop member 52, it permits its free operation by its associated electromagnetic operating means.

Referring to Fig. 5, it will be seen that the inner structure 28 has mounted at one side the core structure 30 of the electromagnet upon which suitable coils are mounted. This core structure 30 has an associated armature structure 65 of non-magnetic material and is provided with a suitable knife-edge bearing 66 and is biased to a deenergized position by a spring 67. This armature structure 65 is provided with an attached armature 64 of magnetic material for

cooperating with the core structure 30. Also, suitable contacts for making and breaking front and back contacts are provided. The bias spring 67 has its tension suitably adjusted by the adjusting screw 68 having a suitable lock nut.

The armature member 65 has an extending forked portion 69 which extends around the plunger 62 and its supporting guide means so as to freely move vertically and to carry at its outer extremities a resilient connector 70. This resilient connector 70 may be made of phosphor bronze spring or the like and extends downwardly through a hole in the base plate 31 of the inner structure 28 to engage the grasping finger portion 71 mounted on the locking stop member 52. Assuming the force drop lock plunger 62 to be released, that is, moved upwardly to a disengaging position, as above explained, then the energization of the electromagnet causes the armature member 65 to be moved to an energized position against the bias of coil spring 67. This breaks the back contacts of the associated contact fingers and closes the front contacts. At the same time, the resilient connector 70 is moved upwardly and to the left, thus transmitting motion to the locking stop member 52 which rotates counter-clockwise as viewed in Fig. 5 to a position in which it does not block the guide holes 54 for the lock rod 50. Under such a condition, any substantial force applied to the foot pedal portion 11 will be transmitted through the arm 49 to the lock rod 50 compressing the spring 51 and causing the lock rod to move through its guide holes 54 freely without interference from the locking stop member 52. When the pedal-latch 11-10 has been moved until its lower portion 56 contacts stop 57, the tappet bar 46 through its lost motion connection will engage the lever 47 to positively insure that the cam shaft 35 is assuming its biased position. Also, the pedal-latch 11-10 will then have been moved counter-clockwise as viewed in Fig. 4 to such a position as to permit the hand lever 9 to be free for operation to an opposite position.

When the hand-throw lever 9 is thus operated, the hold-open lever 20 is moved to such a position beneath the pedal-latch 11-10, as can be seen in Figs. 2 and 4, as to hold the pedal-latch in a releasing position insofar as the hand-throw lever 9 is concerned even though the trainman's foot is removed from the pedal portion 11. This hold-open lever feature is necessary since the relatively strong spring 51 biases the lock rod and the pedal-latch 11-10 toward a locking position, so that whenever the hand-throw rod 9 is restored to its normal position, and the bar 20 is withdrawn from beneath the pedal-latch 11-10, it immediately engages the hand-throw bar 9. However, this does not cause the contact arm 39 to break its back contacts since the cam shaft 35 remains in its biased position until the pedal portion 11 is lifted and the arm 45 causes the tappet rod 46 to be moved to the left as seen in Fig. 4 to act through the lever 47 to compress the spring 37. In other words, the lock latch contacts are not actuated to normal positions until the pedal-latch 11-10 has been moved to such a position that the padlock detent 13 may be moved to hold the latch 10 in a normal position in which the padlock P may be properly inserted.

Referring to Fig. 5, it will be seen that a sealed cover 72 is over a spring biased push button having a button portion 73, a biasing spring 74 and a water-proofing flexible cover 75. This emer-

gency sealed push button, when manually depressed, engages a slidible bar 76 which is held in its normal position by a spring pressed detent 77, but the depression of the plunger 73 engages the bar 76 and moves it downwardly (the detent recess 78 going past the detent 77). The downward motion of the bar 76 engages an extending arm 79 connected to the latch contact arm 39 so that the initial movement of the bar 76 causes the latch contacts to be opened and the front contacts to be closed independently of the position of the cam shaft 35. After the initial movement of the bar 76 and the operation of the latch contacts, the lower end of the bar engages the locking stop member 52 to move it to a non-locking position. This cannot happen however unless the cam shaft 35 is in a biased position permitting the plunger 62 to be moved upwardly to a non-engaging position, which means that the padlock P must be removed and detent 13 actuated to release latch 10 before the emergency push button can be effectively operated.

When the locking stop member 52 is thus released, the pedal-latch 11-10 can of course be moved to a releasing position to allow hand operation of the track switch, but when the hand operation of the track switch has been completed and the hand-throw bar 9 moved to a normal position so that the pedal-latch member 11-10 can be raised, the tappet bar 46 causes the cam shaft 35 to assume its normal position and in so doing the plunger 62 is caused to force the locking stop member downwardly into a locking position. This movement of the locking stop member 52 restores the emergency release bar 76 only to a position where the detent 77 engages the recess 78. This means that the bar 76 still acts through arm 79 to hold the latch contacts open, even though the switch has been restored to normal and padlocked. Holding back contact 81 open holds the signals at stop, which condition continues until a maintainer is called to open the cover 26 and restore the bar 76 to its original position. This action of bar 76 guards against misuse of the emergency release by a trainman.

It should be understood in this connection, that the sealed cover 72 should not be opened and the emergency release button used except under proper emergency conditions, and under such conditions, the trainman at the switch has usually received permission from the central operator via a telephone or other communication means that the switch lock is out of order, or the remote control thereof is ineffective, so that manual release is necessary and safe under the particular conditions in which such emergency release operation is to be employed.

Referring to Fig. 6, the general functions and operations of the electric switch lock can be considered with more particular regard to the specific sequences of operations for a particular operation. It should be understood, however, that the various parts in this functional diagram have been distorted in order to illustrate the functions, and the parts do not necessarily have the same structural forms as found in the structural figures of the disclosure.

More specifically, the removal of the padlock P and the upward movement of the detent 13 permits the latch 10 to operate through a limited free movement so that the tappet bar 46 will allow the coil spring 37 to move the cam shaft 35 to a biased position. This allows the latch contacts 81 and 82 to assume their biased positions

and close their front contacts. With front contact 82 closed, the coils of the electromagnet can be energized through suitable remote control means and any automatic circuits desired. The opening of the back contact 81 also causes the opening of the signal control circuit of any signal or signals governing traffic over the track switch W.

However, the trainman does not step on the pedal 11 until the indicator lamp 33 is illuminated, indicating that the remote operator and the automatic controls have released the electric lock by energization of the electromagnet 30. When the electromagnet is energized, the armature structure 65 opens back contact 84 and closes front contact 83. The back contact 84 further opens the signal circuits, while front contact 83 energizes indicator lamp 33.

When the cam shaft 35 is actuated to its biased position, the lock plunger 62 is moved to a non-engaging position by the spring 63. This permits the resilient connector 70 to operate the stop member 52 to a non-locking position by the energization of the electromagnet 30, thereby permitting the longitudinal movement of the lock bar 50 upon the application of downward force on pedal 11. This movement of the pedal-latch 11-10 to a depressed position releases the hand-throw lever 9 and permits the operation of track switch W to an opposite position. While the hand-throw lever 9 is out of its normal position, the hold-open bar 20 keeps the latch 10 in such a position that the lever 9 can be restored at any time. It is of course understood that the usual holding catch 85 (see Fig. 1) is used for the reverse position of the lever 9, and that this catch can be released by the trainman at any time.

The restoration of the manual throw lever 9 to a normal position allows the lock rod 50 to assume a normal position by reason of the biasing spring 51, and the hold-open bar 20 permits the latch 10 to assume a locking position. As above mentioned, the lifting of the pedal-latch 11-10 (as instructed on the pedal portion) allows the detent 13 to go into a position so that the padlock can be inserted and locked. At the same time, the tappet bar 46 causes the cam shaft 35 to positively assume a position which forces the latch contacts to their normal positions and at the same time forces the plunger 62 downward to insure that the locking stop member 52 is in a locking position. It is obvious that this forcing of the locking member 52 to a locking position acts to apply pressure through the resilient connection 70 on the armature 65 and thus assure that it assumes a deenergized position.

It can be readily seen that the use of the emergency release forces the latch contacts to open positions, but the stop member 52 cannot be moved to a non-locking position by the bar 76 unless the padlock has been removed and the pedal latch allowed to assume its initiating position to allow the plunger 62 to be raised by spring 63. In this way, misuse of the sealed emergency release is prevented by an unauthorized person not having a key for padlock P.

It will also be noted that the locking stop member 52 is of the statically balanced type and the various jars, shocks and vibrations transmitted to the lock does not act to throw it out of a locking position while the padlock detent 13 is released. This is because such jars and vibrations act equally on all sides of the pivot point 53. It is also noted that any shocks or vibration which might cause a slight amount of vibratory action

on the armature structure 65 is minimized by the use of the resilient connection 70.

It is therefore believed that a reliable, positive acting, and efficient switch lock organization has been provided in accordance with the present invention, which organization is constructed so as to be immune to shocks and vibration and to be relatively free from moisture and frost conditions by reason of the double casing structure.

While the present invention has been described rather specifically, it should be understood that this description has been given solely by way of example, and is not intended in any manner whatsoever in a limiting sense. Obviously the invention can assume many physical forms, and is susceptible of various modifications, and it is intended to include in this invention all such forms and modifications as come within the scope of the appended claims.

Having described our invention, what we claim is:

1. In an electric lock for hand-operated track switches, a manually operable lever for moving the points of a track switch to their opposite positions, a manually operable catch for preventing operation of said lever subject to the release of an electric lock mechanism comprising a longitudinally movable cam shaft, contacts operated by said cam shaft to their closed positions when said cam shaft is in a predetermined position, a lock member for preventing manual operation of said catch until released, electromagnetic means for releasing said lock member, and means for positively forcing said lock member to be in a locking position when said cam shaft is in said predetermined position.

2. In an electric lock for hand-operated track switches, a manually operable lever for moving the points of a track switch to their different positions a manually operable catch for preventing operation of said lever when held in its normal position, means for holding said catch in its normal position comprising a lock bar associated with said catch and moved longitudinally when said catch is manually operated to a released position, a pivoted stop member normally preventing longitudinal movement of said lock bar to thereby prevent the manual operation of said catch, an electromagnet of the tractive type, and a resilient connection between said electromagnet and said stop member for causing a limited amount of rotation of said stop member when said electromagnet is energized to thereby release said catch for manual operation.

3. In an electric lock for hand-operated track switches, a manually operable lever for moving the points of a track switch to their opposite normal and reverse positions, a manually releasable catch for preventing operation of said lever from its normal position, a lock bar associated with said catch and moved longitudinally when said catch is manually operated to a released position, a pivoted balanced stop member normally preventing longitudinal movement of said lock bar to thereby prevent the manual release of said catch, and electromagnetic means rotating said stop member a limited number of degrees on its pivot point to at times allow the manual release of said catch, whereby the balanced stop member is substantially immune to shocks and vibration which might otherwise cause a false release of said catch.

4. In an electric lock for hand-operated track switches, a manually operable lever for moving

the points of a track switch to their opposite normal and reverse positions, a manually operable catch for normally preventing operation of said lever away from its normal position, a lock plunger operably connected to said catch so as to be moved longitudinally by the operation of said catch to its locking and released positions, a locking member statically balanced on a pivot point for normally engaging said locking plunger to prevent said catch from being manually released, and electromagnetic means for operating said locking member to a non-engaging position, whereby said catch cannot be falsely released due to shocks and vibration since said balanced locking member is immune to shocks and vibration.

5. In an electric lock for hand-operated track switches, a manually operable lever for moving the points of a track switch to their normal and reverse positions, and an electric lock mechanism for normally preventing manual operation of said lever comprising, a locking plunger operable longitudinally to release said lever, a pivoted locking member statically balanced about its pivot point for in one position preventing longitudinal movement of said lock plunger and in another position for permitting movement of said lock plunger, an electromagnet having an armature normally biased to a deenergized position, and resilient means interconnecting said armature and said pivoted locking member, whereby energization of said electromagnet actuates said pivoted locking member to a non-locking position, and whereby holding of said locking member in either position does not prevent said armature from moving to a non-corresponding position.

6. In an electric lock for hand-operated track switches, a latch for normally locking a track switch to prevent operation of the track switch from its normal position, electromagnetic means for normally holding said latch in its locking position until energized, contacts manually operable from one position in which a signal circuit is closed to another position for permitting energization of said electromagnetic means, and means acting upon the manual restoration of said contacts to said one position for positively forcing said electromagnetic means to its normal position for holding said latch in its locked condition, whereby the restoration of said electromagnetic means is self-checking.

7. In an electric lock for hand-operated track switches, a manual lever for moving the points of a track switch to their opposite positions, a catch for holding said manual lever in a particular one of said positions secured by a padlock in such position, a lock member for restricting the movement of said catch, a latch contact block having normal and operating positions, means effective after the removal of the padlock from said catch for causing said contact block to assume said operating position, electromagnetic means for operating said lock member to allow the complete manual release of said catch in response to the movement of said contact block to said operating position, and manual release means having normal and operated positions, said release means being effective when manually moved to its operated position for operating said lock member to allow the complete release of said catch irrespective of said electromagnetic means, and said means being effective to operate said lock member only when said padlock is removed from said catch.

8. In an electric lock for hand-operated track switches, a manual lever for movement of the

points of a track switch to their opposite positions, a catch for holding said manual lever in a particular one of said positions and secured by a padlock in such position, a lock member for restricting the movement of said catch, a latch contact block having normal and operated positions, a spring for biasing said latch contact block to an intermediate position, means dependent upon the action of said spring for causing said contact block to assume said operated position after the padlock is removed from said catch, electromagnetic means for operating said lock member to allow the complete manual release of said catch in response to the movement of said contact block to said operated position, manually operable means for operating said lock member to allow the complete manual release of said catch irrespective of said electromagnetic means, said manually operable means being effective to release said catch only when said padlock is removed from said catch, and means for causing said latch contact block to be restored to its normal position upon the complete operation of said manual lever and the locking of said catch by said padlock, only if such operation has been effected by said electromagnetic means rather than said manually operable means.

9. In an electric lock for hand-operated track switches, a manual lever for moving the points of a track switch to their opposite positions, a catch for holding said manual lever in a particular one of said positions, a lock member for restricting the release of said catch, a contact block having normally closed contacts, electro-responsive means for releasing said locking member and thereby releasing said catch, manually operable emergency release means for releasing said lock member and thereby releasing said catch, and contact operating means for operating said contact block to open its contacts when said catch is released from its holding position, said contact operating means being effective to restore the contacts of said contact block to their closed positions upon the manual restoration of said catch to its holding position, only if the release of said catch has last been effected by said electromagnetic means rather than by said emergency means.

10. In an electric lock for hand-operated track switches, a manual lever for moving the points of a track switch to their opposite positions, a catch for holding said manual lever in a particular one of said positions secured by a padlock in such position, a lock member for restricting the movement of said catch, a latch contact block having normal and operating positions, means effective after the removal of the padlock from said catch for operating said contact block to its operating position, electromagnetic means for operating said lock member to allow the complete manual release of said catch in response to the movement of said contact block to said operating position, manual release means having normal, intermediate, and operated positions, said manual release means being effective when moved to its operated position to allow the complete release of said catch, irrespective of said electromagnetic means, and said manual release means being effective only after said padlock is removed from said catch, means for operating said latch contact block to restore to its normal position after the restoration of said catch if the release of said catch has been effected by the operation of said electromagnetic means, and means for allowing said manual release means to be restored only to

11

its intermediate position after the locking of said
catch with said padlock.

OSCAR S. FIELD.
RALPH W. HEWES.
